CLAIM

We claim the ornamental design for footwear, as shown and described.

DESCRIPTION

FIG. 1 is a bottom view of footwear, showing our new design;

FIG. 2 is a front, bottom perspective view thereof; and, FIG. 3 is a back, bottom perspective view thereof.

The regular dashed lines are included for illustrating environmental structure and form no part of the claimed design. The dash-dot-dash lines are boundary lines indicating the boundary of the claimed design and form no part of the claimed design.
